UNITED STATES PATENT OFFICE.

GEORGE J. MCGANN, OF WARWICK, RHODE ISLAND, ASSIGNOR TO SLASHER ROLLS CO., OF BOSTON, MASSACHUSETTS, A CORPORATION OF MASSACHUSETTS.

RINSING MACHINE.

Application filed April 12, 1928. Serial No. 269,438

The invention relates to an improvement in rinsing machines of the type for rinsing yarn or fabric in rope form.

In the general operation of the machine 5 the rope of yarn or fabric is run around separate rolls and the passage of the rope is apt to wear grooves in the rolls necessitating a continual renewal thereof and, as the rolls are expensive, the difficulty is a serious 10 one.

The object of the invention is to obviate wear upon the rolls during the operation of the machine.

The invention can best be seen and understood by reference to the drawings, in which—

Figure 1 is a side elevation of the improved machine.

Fig. 2 is a section on the line 2—2 of 20 Fig. 1.

Fig. 3 is a section on the line 3—3 of Fig. 2.

Fig. 4 is a section on the line 4—4 of Fig. 2, and

Fig. 5 is a section on the line 5—5 of Fig. 2.

Referring to the drawings:—

1 represents a tank containing the rinsing fluid. On this tank is mounted a combined 30 frame and casing 2. Turning within the tank 1 is a feed roll 3. This roll is fixed to a shaft 4 the opposite ends of which project through the ends of the tank 1 and through the bottom of the casing 2 which envelops the tank, and are journaled to turn in bearings 5 fixed to the adjacent sides of the casing. Arranged within the top of the casing above the tank is a feed roll 6. This roll is mounted on a shaft 7 the opposite 35 ends of which extend through openings in the opposite sides of the casing and are journaled to turn in boxes 8 fixed thereto, the ends of the shaft turning at the bottom ends of vertical ways formed within these 40 boxes. Mounted also within the casing and above the feed roll 6 is a press roll 9. This roll is mounted upon a shaft 11 the opposite ends of which extend through slotted ways 12 in the opposite sides of the casing and 45 into the ways 13 of the boxes 8, which permits of vertical movement being afforded the press roll toward or away from the feed roll 6 with which it is co-operating.

14 is the yarn or fabric rope. This is 50 directed to enter the machine through an

eye 15 in the top of the casing adjacent the inner end of the press roll 9. Entering the casing the rope passes down through the casing over and around the inner end of the feed roll 3, thence upward over and around the inner end of the feed roll 6 and between this roll and the press roll 9. Thence the passage of the rope is continued with coils passing over and around the respective feed rolls 3 and 6 and between the feed roll 6 60 and the press roll 9, the rope eventually having a run upward from the outer end of the feed roll 3 over the outer end of the feed roll 6 and thence over the outer end of the press roll 9 and through the adjacent 70 back of the casing, leaving by way of an eye 16 therein.

Mounted upon the opposite sides of the casing 2 with extension through the loops formed by the runs of rope between the feed 75 rolls 3 and 6 is a bar 17. Fixed to this bar with lateral projection therefrom are a series of spaced pins 18. The arrangement of the bar 17 and the extension of the pins 18 are such that the pins will project outwardly 80 between the several runs of rope which are passing upward over the roll 3 and onto the roll 6, and operate to hold the coils of rope at properly spaced intervals apart on the respective rolls and around which the rope 85 is passing.

The pins 18 function also to move the coils of rope back and forth over the faces of the respective rolls over which the rope is passing in order that the rope may evenly traverse the entire surface of these rolls during the operation of the machine and not run along a single line or track thereon. To this end the bar 17 carrying the pins is mounted upon the sides of the casing to have an end- 90 wise sliding or reciprocating movement thereon, the opposite ends of the bar passing outwardly through slots or openings in the opposite sides of the casing with projection beyond the outer sides or faces thereof. Brackets 19 on the outer sides of the casing 95 provide bearings for these projecting ends of the bar and on which bearings the bar slides. The bar 17 is moved back and forth with a relatively slow movement of determinate extent in reverse directions or with such extent of movement as will cause the pins by their bearing against the runs of rope, between the rolls over and around which the rope is passing, to gradually move 100 105 110

the coils of rope back and forth as aforesaid over the faces of the respective rolls.

The reciprocation of the bar 15 is effected by the operation of the machine as follows:—

- 5 Arranged on the outer end of the shaft 7 carrying the feed roll 6 beyond the side of the casing is a worm 20 which meshes with a worm wheel 21 arranged on the top end of a vertical shaft 22 which turns in spaced 10 bearings 23 carried by brackets 24 secured to the side of the casing. At its lower end the shaft 22 is provided with a hub 25. Projecting from this hub is a crank arm 26 having in it a slot 27. Adjustably fixed to the 15 crank arm is a pin 28. This pin projects through the slot 27 in the arm and is fixed in any adjusted position along this slot by nuts 29 on the pin engaging the opposite sides of the arm. Pivoted to the pin 28 is a 20 link 30 which pivotally connects with a pin 31 fixed to the outer end of the bar 17.

The machine is operated by power applied to a pulley 32 arranged on the end of the shaft 7 which bears the feed roll 6. As this 25 shaft is rotated the rope will be made to pass around the respective feed rolls and at the same time, through the worm 20 on the end of the shaft, the worm wheel 21 and the shaft 22, power will be applied to turn the 30 crank arm 26 which as it is turned will through the link 30 operate to move the bar 17 back and forth and thereby through the pins 18 on the bar cause the various coils of rope to traverse evenly back and forth over 35 the entire surface of the respective rolls over which the rope is passing. The extent of traverse of the coils of rope is determined by the distance that the bar 17 is moved or reciprocated back and forth, taking into consideration the speed at which the rope is 40 moving and also the speed at which the bar 17 is being reciprocated, and all this is determined and a proper reciprocation given the bar 17 to obtain the desired result by a determinate fixing of the throw of the crank 45 arm 26 and this is obtained by a properly adjusted fixing of the link pin 28 to the crank arm.

Having thus fully described my invention, I claim and desire to secure by Letters Patent of the United States:—

1. In a rinsing machine having a feed roll over which coils of the material to be rinsed are severally passed to be fed by the roll, the combination therewith of, means whereby coils of the rope will be directed to traverse longitudinally back and forth over the surface of said roll as the rope is fed by the roll during the operation of the machine.

2. In a rinsing machine having a feed roll over which coils of the material to be rinsed are severally passed to be fed by the roll, the combination therewith of, means 60 governing the paths of said coils over said

roll whereby they will collectively traverse longitudinally back and forth over substantially the entire surface of said roll.

3. In a rinsing machine having a feed roll over which coils of the material to be rinsed are severally passed to be fed by the roll, the combination therewith of, spacing elements between which said coils are directed to run, a movable carrier for said elements adapted and arranged whereby endwise reciprocating movement thereof will through said elements change the paths of said coils and direct them to traverse back and forth over the surface of said roll as the coils are fed by the roll during the operation of the machine, and means for imparting endwise reciprocation to said carrier.

4. In a rinsing machine having spaced feed rolls around which coils of the rope of material to be rinsed are severally passed to be fed by the rolls, the combination therewith of, spacing elements arranged between the two rolls and between which elements running portions of the several coils of the rope are directed to pass, a carrier for said elements adapted and arranged whereby endwise reciprocating movement thereof will through said elements change the paths of said coils and direct them to traverse back and forth over the surfaces of said rolls as the rope is fed by the rolls during the operation of the machine, and means for imparting endwise reciprocation to said carrier.

5. In a rinsing machine having a feed roll over which coils of the material to be rinsed are severally passed to be fed by the roll, the combination therewith of, spacing elements between which said coils are directed to run, a movable carrier for said elements adapted and arranged whereby endwise reciprocating movement thereof will through said elements change the paths of said coils and direct them to traverse back and forth over the surface of said roll as the coils are fed by the roll during the operation of the machine, means for imparting endwise reciprocation to said carrier, and means whereby the extent of reciprocating movement of said carrier may be 115 adjustably changed.

6. In a rinsing machine having a tank, spaced feed rolls around which coils of the rope of material to be rinsed are severally passed to be fed by the rolls, one of said feed rolls being arranged within said tank 120 and the other of the feed rolls being arranged above the tank spaced from the feed roll within the tank, and a press roll bearing against said other of the feed rolls, the combination therewith of, spacing elements arranged between the two feed rolls and between which elements running portions of the several coils of rope are directed to pass, a carrier for said elements adapted and arranged whereby endwise reciprocating 125

movement thereof will through said elements change the path of said coils and direct them to traverse back and forth over the surfaces of said rolls as the rope is fed by the rolls during the operation of the machine, means whereby power may be applied to one of the feed rolls for operating the machine, and means whereby said carrier may be reciprocated through mechanism connecting with one of the feed rolls.

7. In a rinsing machine having a tank, spaced feed rolls around which coils of the rope of material to be rinsed are severally passed to be fed by the rolls, one of said feed rolls being arranged within said tank and the other of the feed rolls being arranged above the tank spaced from the feed roll within the tank, and a press roll bearing against said other of the feed rolls, the combination therewith of, spacing elements arranged between the two feed rolls and between which elements running portions of the several coils of rope are directed to pass, a carrier for said elements adapted and arranged whereby endwise reciprocating movement thereof will through said elements change the path of said coils and direct them to traverse back and forth over the surfaces of said rolls as the rope is fed by the rolls during the operation of the machine, means whereby power may be applied to said other of the feed rolls, mechanism operated by said other of the feed rolls including a crank arm, a link connection between said crank arm and said carrier, and means for adjustably fixing said link connection to the crank arm.

GEORGE J. McGANN.
